Julius Meyer, of Cincinnati, O.
Letters Patent No. 944. Dated Sept. 29. 1857.

The schedule referred to in these Letters Patent, and making part of the same.

To all whom it may concern:

Be it known that I, Julius Meyer, of the city of Cincinnati, in the County of Hamilton, and State of Ohio, have invented or produced a new design for a stand for Shovel & Tongs, and I do hereby declare that the Vine and Leaf work, represented in the annexed drawing, is a full and exact description of the same.

What I claim and desire to secure by Letters Patent is the new design for a Shovel & Tongs stand, consisting in the ornamental figures, of the base or dish, the upright - the arms or hook and the handle - as set forth in the accompanying drawing.
